UNITED STATES PATENT OFFICE

MICHAEL MAUL, OF BERLIN, GERMANY, ASSIGNOR TO THE TABULATING MACHINE COMPANY, OF ENDICOTT, NEW YORK, A CORPORATION OF NEW JERSEY

ACCOUNTING MACHINE FOR PUNCHING TOTALS

Application filed July 30, 1927, Serial No. 209,457, and in Germany November 20, 1926.

This invention relates to accounting systems wherein data on record cards or sheets bearing index points is automatically read, computed, printed, etc. In such systems, it is often found desirable to utilize cards wherein data punched thereon includes items entered into an accumulator of an accounting device.

The object of the present invention is to control punching mechanism from the accounting device to effect automatic punching on a record card of the items entered into the accumulator, said record card having additional data punched therein by manual operation of the punching mechanism.

The object of this invention is further to automatically punch a total standing on accumulating elements.

Another object of this invention is to control the selection of the punches for perforating a record card in accordance with the position of the accumulating elements.

Another object of this invention is to control the selection of printing elements and punching elements by the same accumulator to respectively print and punch the data entered into the accumulator.

Fig. 1 is a plan view of the perforating mechanism,

Fig. 2 is a longitudinal sectional view thereof,

Fig. 3 is a detail of the punching mechanism,

Fig. 4 is a view of an accumulator section of the accounting mechanism.

Fig. 5 is a side view of the accumulating wheels and the punch selecting wheels geared thereto,

Fig. 6 is a circuit diagram of the punch selecting mechanism,

Figs. 7 and 8 are details of the column selector.

Referring to Fig. 1, B indicates the card punching structure. The latter is described in detail in the U. S. Patent No. 1,821,078 owned by the assignee of the present invention. In brief, the operation of the punching mechanism is as follows: A stack of cards to be punched is placed in magazine 10. The operator draws out a rod 11 which carries one

card from the bottom of the stack forward into the punching section of the machine. Thereafter when the keys are manipulated by the operator, the card is advanced forward one column at a time by the escapement mechanism, the escapement operating at each punching operation. These parts are described in greater detail in the application above referred to. After the card is punched, the operator withdraws the card at the left end of the machine, re-operates pull-rod 11 and punches the next card. For each index position on the card, a punch 12 is provided, a series of said punches being placed in a row across the device. Corresponding to each punch is a finger key 13 for manual operation. Action of the key serves to depress plunger 14, which by rocking bell crank 15 pivoted thereto at 16, thrusts forward an interposer bar 17 to an advanced position over its corresponding punch 12. The forward movement of an interposer rocks an arm 18 in its path, which pulls a link 19 forward and thus closes contacts 20. This establishes a circuit to the main punching magnet 21 which attracts its armature 22. An arm 24 (Fig. 3) is fixed to a rock shaft 60 to which is also affixed a bail 23. The free end of arm 24 is connected to armature 22 by an adjustable link 61 so that attraction of the armature causes shaft 60 to rock, thereby lowering bail 23 from a normally raised position shown in Fig. 2 to the lower position shown in Fig. 3. Bail 23 is directly over the row of punches 12 and when rocked downwardly depresses any of the interposer bars which have been moved forward, and thereby forces the punch or punches through the card. Punches whose interposer bars have not been thrust forward will not be affected, as they will be in the position shown in Fig. 1 with the clearance notch 25 under the bail. Contact 26 (Fig. 1) is provided to cut out the punch selecting magnets 42 while pull-rod 11 is being operated in order to prevent punching operations during that time (as fully explained in aforementioned Patent No. 1,821,078, page 13, line 111 through line 13 of page 14, in connection with Figs. 3 and 13).

After each column of the card is punched, 100

escapement mechanism operates to feed the next card column under the punches 12. The card being punched rests on top plate 62. A card carriage comprising a rack 63 has an extending arm 64 at the rear carrying a pivoted member 65 which drops behind the rear edge of the card being fed and a hold-down cam gripper 650 which engages and holds down the forward end of this card. The rack 63 has gear teeth on its lower edge meshing with a gear 66 forming part of the casing of a drum enclosing a spiral spring. As the carriage is moved to the right in Fig. 3 the rack rotates gear 66 and tensions the drum spring which thereupon tends to move the carriage back to the left. This movement to the left is controlled by escapement mechanism responsive to the punching operation. A bail 70 is mounted on shaft 71 and extends beneath all the interposer bars 17 so that when an interposer is lowered to effect punching the bail 70 is rocked counterclockwise against the action of a biasing spring (not shown). A pawl 73 is loosely mounted on shaft 71 and a spring 72 attached to an extending arm of the pawl tends to force it into engagement with a series of notches formed on the upper edge of rack 63. A second pawl 80, pivoted on the machine frame, cooperates with pawl 73 to form an escapement. A double arm member 81 is also mounted on shaft 71 and arranged to be operated by bail 70. This member is connected to pawl 80 through a pin and slot connection and to pawl 73 by means of a pin 75 engaging an enlarged hole in the pawl. Normally when the bail 70 is in raised position the member 81 holds pawl 80 free of the ratchet teeth and holds pawl 73 in engagement with one of them.

On a punching operation the lowering of one of the interposers 17 moves bail 70 downward and consequently rocks member 81. This first moves pawl 80 into engagement with the ratchet teeth to hold the card carriage against movement temporarily and then, owing to the cooperation of pin 75 with the enlarged hole, raises the pawl 73 free of the ratchet teeth. The spring 72, on account of the loose mounting of pawl 73 moves it slightly into position to engage the next ratchet tooth. Then, on the rise of bail 70 after the punching in the particular card column, the pawl 80 is raised and the card carriage moves until pawl 73 engages the next ratchet tooth stopping the carriage with the next card column under the punches. This mechanism is well understood and fully described in the Patent No. 1,821,078 heretofore mentioned and in patent to Schaaff, No. 1,426,223, 60 August 15, 1922.

The manual operation of the punching mechanism above described is, by means of this invention, to be combined with an automatic operation of the punches controlled by 65 counting or computing mechanism, prefer-

ably that of a tabulating machine. Any such suitable accumulating, tabulating or counting mechanism may be used for the proper carrying out of the invention but for the purposes of the disclosure, the description and drawings have been confined to the tabulating counting mechanism described in the co-pending application of C. D. Lake, Serial No. 639,153, filed May 15, 1923, owned by the assignee of the instant case now Patent No. 1,822,594. The accumulator driving, carrying, and other mechanism related to the accumulators are all well known features of the prior art (see for example Lake Patent No. 1,307,740 for driving features of the accumulators and refer therein to page 2, lines 119 and 122 and see Hollerith Patent No. 974,272 for the transfer mechanism).

In Fig. 4 (corresponding to Fig. 20 of Patent No. 1,822,594) is shown one of the tabulating counter sections of the Lake tabulator. Each counter section includes counter magnets 27 for controlling the movement of counters 28 in accordance with the index points on the record card then under the lower one of two sets of analyzing brushes. The tabulating machine, as explained in detail in Patent No. 1,822,594 has an automatic control which changes the operation of the machine in accordance with the groups of cards having been tabulated. This control is exercised from a selected group of index points in adjacent card columns. So long as each consecutively fed card has the same group of index points as the preceding card the machine will continue to accumulate the items on the cards and may also list them. When the selected group of index points of a card is not the same as that of the preceding card, the automatic control operates in either of two ways, depending on the preliminary setting of certain control switches. According to one mode of operation, the automatic control upon a group change may initiate a total printing operation and a resetting operation. According to the other mode of operation, the machine automatically stops after a group change and the total printing and resetting operations are initiated manually. Total printing, as usual, may be effected from a stepped cam 31 which is geared to the counter wheel and thus always positioned according to the reading on the wheel. The position of this cam is felt out during totaling by a rockable finger 32. When an adjustable screw 33 on the end of this finger encounters the uppermost step of the cam 31 contacts 34 and 35 are closed to energize printing magnets (not shown) to select the type for printing which correspond to the reading of the counter wheel. The purpose of the present invention is to automatically punch on a record card, the readings of a certain group of said counters after they have come to rest.

The readings punched will obviously be the totals of the items in certain columns of the last group of tabulated cards. This punching may be either in addition to or in lieu of 5 total printing. Geared to each counter wheel 28 (Fig. 4) through an idler gear is a gear wheel 36 freely rotatable on shaft 37. Associated with each gear 36 is a stationary contact ring 38, fixed to a stationary shaft 37 and insulated therefrom. Encircling each ring 38 and fixed thereto is a commutator ring 39. The commutator ring is provided with ten conducting segments 40 insulated from each other and from the contact ring 38. 10 15 A brush 41, fixed to gear 36 to rotate therewith, is in constant engagement with ring 38 and is adapted to contact segments 40 successively to conductively connect the segments in turn with the ring 38. Each of the 20 segments 40 corresponds to a numeral on the counting wheel 28 and when a particular numeral on the wheel is at reading position, the segment 40 corresponding to said numeral will be in contact with the brush 41. 25 Each gear 36, contact ring 38, commutator ring 39 and brush 41 constitute a punch selecting unit. There are as many such selecting units as the number of counting wheels but for the purposes of illustration, only 30 three are shown in Fig. 6, the one characterized by an *a* after its reference numerals being controlled from the units counter 28*a* of a group of adjacent denominational order column counters, the selector unit with *b* after 35 the reference characters corresponding to the tens counting wheel of said group, and the one with *c* corresponding to the hundreds counter of the group.

In series with each of the commutator segments 40 is a magnet 42 corresponding to and adapted for actuating one of the interposers 17. The magnets are connected at one end by a common lead 43 to similar segments on each of the commutator units. Since only 45 one column at a time is punched, only ten selecting magnets are provided for cooperation with all of the tabulating counters. Each magnet corresponds to the numeral characterizing the commutator segments with 50 which it is in series and operates the punch for perforating the card to designate said numeral.

The aforementioned punch selecting units and the magnets 42 are associated with a column selector commutator in the punching machine. This commutator comprises a frame bar 47 fixed to the punch frame 470 in any suitable manner, as for example, by an end bracket 471 and a bottom angle bracket 472 (see particularly Fig. 8). Mounted on top of frame bar 47 and insulated therefrom is a rear contact rail 45 and insulated from the latter is a row of contact sections 46 insulated from each other and carried by the bar 47.

The magnets 42 are in series with one side of a source of current 44, the other side of which connects to the contact rail 45. The center lines of sections 46 are a card column apart and the number of sections equals the number of columns on a card. Rigidly connected with the card holding carriage of the punching mechanism by means of a bracket 473 secured to rack 63 and a plate 474 is a contact piece 48 (Figs. 1, 7 and 8) for conductively connecting contact rail 45 and the sections 46. As the carriage, after a punching operation, moves a distance of one card column, the contact piece 48 also moves the same distance and thus connects each of the sections 46 in succession to the rail 45. 10 15 20 25 30

Each of the contact rings 38 of the selectors, except the one corresponding to the units counter, is removably plugged to one of the contact sections 46. For a purpose hereinafter set forth, the units counter ring 38 is connected to rail 45 through normally open contacts 50, the lead 51*a* from the ring being removably connected to one side of contacts 50. The ring 38*b* of the commutator for the tens counter is removably connected by lead 51*b* to the section 46*b* corresponding to the card column in which the data on said tens counter is to be punched. The ring 38*c* is removably connected by lead 51*c* to the section 46*c* corresponding to the card column in which the data on the hundreds counter is to be punched. Thus if the data on the units counter is to be punched in the twentieth column of the card in the punching mechanism, the tens counter 28*b* will be associated through the ring 38*b* with section 46*b* corresponding to the twenty-first column and the hundreds counter will be associated through ring 38*c* with section 46*c* corresponding to the twenty-second card column. The removable connections of the rings 38 to column sections 46 permits selective association of any of the counting wheels with any of the column sections. 100 105 110

The mode of operation of the parts described is as follows: The operator manually actuates keys 13 to perforate data in the card columns preceding those which are to be perforated automatically in accordance with the reading on the counters of said tabulating machine. In this preliminary manual operation of the punching machine, if any column is not to contain any of items 1 to 9, the "0" key may be depressed to cause the "0" position of the column to be perforated. If it is not desired to thus perforate columns in their zero position, the operator depresses the "skip" key 90 (see Fig. 1) as is well understood in the art. This "skip" key shown in Fig. 1 advances an interposer 17 and causes its depression to effect a feeding operation in the same way as any numeral key. The particular interposer connected to the "skip" key is not, however, provided with a forward 115 120 125 130

portion such as 25 to engage any punch. Therefore, upon its depression, there is no punching operation but only a feeding operation as above explained. The details of this particular skip key construction are fully disclosed in Patent No. 1,803,979. Due to the geared connections of the commutator brushes 41 to the counters the commutator brushes will rotate in synchronism with the counters and when the counters are at rest, will contact with the commutator segments 40 corresponding to the reading on the counters. The punch carriage 49 in the meanwhile, has been moved so that the bridging contact 48 overlies section 46a corresponding to the units column of the item to be punched. The punching of the card in this column in accordance with the reading of the units counter is placed under control of the punch operator in order that upon the completion of a manual punching, the automatic punching may not follow directly without the knowledge of the operator. For this reason, the units sliding ring 38a is not connected to section 46a but to the common contact rail 45 through the normally open contacts 50 as hitherto explained. The card column corresponding to the units counter being under the row of punches after the tabulating machine is at rest, the operator depresses key 52 closing contacts 50, completing the circuit through one of the magnets 42 which thereupon attracts its armature 53 (Figs. 1 and 3) depressing plunger 14 and effecting an operation of the punch as in the manual operation. The punch carriage 49 after the punching operation automatically advances the card to the next column moving bridging contact 48 with it to connect contact section 46b with the common bar 45. A circuit is thereby completed which energizes the magnet 42 in series with the commutator segment 40b engaged by the commutator brush 41b. Magnet 42 upon energization effects the punching of the card in said column. As the carriage continues to move a column space after each punching operation, the contact sections 46 are successively engaged by the contact 48 to automatically cause punching of the reading on the counters associated with the successive sections 46.

It is understood that the particular punching device herein described is not necessary to carrying out the invention, but similarly functioning punching devices may also be used in connection with the invention. It is also obvious that the accumulating means to be used are not necessarily those described herein but that it is within the scope of this invention to associate any similar accumulating mechanism with selectors for automatically operating a punching device to punch the data standing on the accumulating mechanism.

What is claimed is:

1. An accounting machine comprising a plurality of denominational order accumulating elements having means for effecting concurrent data entries therein, a punching mechanism, manual means for initiating operation of the punching mechanism in accordance with the data entered into the first denominational order accumulating elements, and automatic means for causing operation of the punches in accordance with the data entered into the accumulating elements above the first denomination. 70

2. A device for automatically operating a punching machine provided with punches and card feed mechanism to perforate a record card in accordance with the reading of the accumulating mechanism of an accounting machine, comprising punch selecting means, and means for operating the same in synchronism with the operation of the accumulating mechanism and means controlled by the card feed mechanism of the punching machine in accordance with the position of the card relative to the punches and associated with the first mentioned means to control an automatic operation of the punches to perforate the card in accordance with said reading. 80

3. A device for automatically operating a punching machine having a card feeding carriage to perforate a record card in accordance with the reading of accumulating mechanism, comprising means controlled by the position of said carriage to determine the card columns in which the reading is to be punched and means controlled by the accumulating mechanism to determine the position of the perforations in the columns. 90

4. A device for automatically operating a punching mechanism including punches to perforate a record card in accordance with the reading of accumulating means, comprising means controlled by said accumulating means for selecting the punches to be automatically operated and means controlled by the punching mechanism for selecting the columns to be perforated. 100

5. A device for automatically operating a punching mechanism including punches to perforate a plurality of adjacent columns in accordance with the reading of accumulating elements, comprising means operated in accordance with the reading of said accumulating elements for selecting the punches for operation, means operated by the punching mechanism to select the card columns to be perforated, and means for placing the perforating operation in the first of the columns selected for perforation under the control of the operator, the remaining columns being automatically punched. 115

6. In combination, an accounting mechanism having accumulating elements with means for effecting record entries therein, 130

- punching means to punch parallel columns of a record card, means for selectively operating the punches, and means for selectively interchangeably, and readily releasably connecting any of said accumulating elements to said punch operating means to cause punching of any desired column of the record under control of any one of said accumulating elements in accordance with the data entered into said accumulating element.
7. In combination, punches for perforating a record sheet, electrical operating and selecting means for the punches, item receiving members, electrical connections between the item receiving members and the punch operating and selecting means, a manually controlled switch for rendering the connections of one item receiving member effective to cause the punch operating and selecting means to operate the punches in accordance with the item carried by the last-named item receiving member, and switches in the connections between the other item receiving members and the punch selecting and operating means automatically operated to cause operation of the punch selecting and operating means in accordance with the item carried by the last-named item receiving members.
- In testimony whereof I hereto affix my signature.

MICHAEL MAUL.
